UNITED STATES PATENT OFFICE

2,535,375

PLIERS

Harold W. Stark and Roy A. Grant,
Marinette, Wis.

Application November 17, 1947, Serial No. 786,358

2 Claims. (Cl. 32—62)

1

This invention relates to pliers having adjustable clamping jaws.

An object of this invention is to provide a pair of pliers which include a pair of pivotally connected together handles or pressure levers, a pair of article clamping jaws pivotally connected to said handles, and an adjustable fulcrum pin connected between said jaws.

Another object of this invention is to provide a pair of pliers which include a pair of pivotally connected together handles or pressure levers, a pair of article clamping jaws, and means pivotally securing the rear ends of said jaws to said handles in a manner to rock said jaws to clamping position when said handles are swung toward each other.

Another object of this invention is to provide a pair of pliers of this kind which are particularly designed for use as dental forceps and which include means for adjusting the jaws relative to each other so as to grip an article of predetermined size when the handles are closed, the handles when closed placing substantially the same pressure on the article irrespective of the size of the article inasmuch as the jaws have the same movement relative to each other irrespective of the size of the article.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a detailed side elevation of a pair of pliers constructed according to an embodiment of this invention.

Figure 2 is a plan view of the pliers.

Figure 3 is a longitudinal section through the forward end of the pliers showing the jaws in open position.

Figure 4 is a sectional view taken on the line 4—4 of Figure 1.

Figure 5 is a sectional view taken on the line 5—5 of Figure 1.

Referring to the drawing, the numerals 10 and 11 designate generally a pair of elongated handles. The handle 11 is substantially shorter in length than the handle 10 and is provided at its rear end with an outwardly curved rear portion 13. The handle 10 at its forward end portion is provided with an angularly disposed pair of ears 55

2

12 between which an angularly disposed ear 14 is carried by the forward end of the handle 11 is adapted to engage. The ears 12 and 14 are pivotally connected together by means of a pivot 15. A pair of jaw members, generally designated as 16 and 17, extend from the handles 10 and 11, respectively. The jaw member 16 is pivotally connected to the forward end of the handle 10 by means of a pivot 18 which is offset laterally from the pivot 12 and the jaw member 17 is pivotally connected to the forward end of the handle 11 by means of a pivot 19 which is offset laterally from the pivot 15. The jaw member 16 includes an elongated shank 20 which is provided with a curved forward end 21 terminating in a pressure applying jaw 22.

The jaw member 17 includes an elongated shank 23 disposed in parallel relation with respect to the shank 20 when the handles 10 and 11 are in closed position. The shank 23 has extending therefrom a complementary forward end portion 24 and a pressure applying jaw 25 is carried by the extension 24.

In the present instance, as shown in Figure 5, the pressure applying jaws 22 and 25 are formed with concave confronting faces 26 and 27, respectively. The jaws 16 and 17 are adapted to be constantly urged apart by means of a flat spring 28 which extends between the shanks 20 and 23, bearing at its outer portion against the shank 20 and provided with an inner portion 29 which bears against the ear 14. The jaw members 16 and 17 are pivotally connected together and are adjustable relative to each other by means of a threaded bolt 30 which is extended through the shanks 16 and 17 and is provided with a head 31 engaging in a socket 32 formed in the shank 23.

The shanks 20 and 23 are provided with openings 33 and 34, respectively, through which the bolt 30 loosely engages and a nut 35 is adjustably threaded on the bolt 30 and bears against the outer side of the shank 20. The bolt 30 constitutes the fulcrum or pivot member for the jaws 16 and 17 and is adapted to be adjusted to provide for the desired opening between the outer jaw or pressure applying members 22 and 25.

In the use and operation of these pliers the jaw members 16 and 17 are initially roughly adjusted relative to each other by adjustment of the nut 35 on the bolt 30. This will permit the spring 28 to move the outer ends of the jaws apart a distance sufficient to receive the article which is to be engaged by the jaws therebetween. The rocking of the handles 10 and 11 toward

each other will provide for limited movement of the outer ends of the jaws toward each other so that the necessary pressure of the jaws on the article will be limited and the handles 10 and 11 will normally be in closed position when the article is clamped between the jaws. These pliers have been designed partly as dental pliers or forceps so that the necessary pressure may be applied to a tooth in extracting the latter and the jaws will not be placed under undue pressure during the extracting operation. In this manner the tooth will not be broken off by application of excessive pressure such as is the case where ordinary pliers are used.

Due to the offset connection between the handles 10 and 11 and the clamping members 16 and 17, respectively, when the handles 16 and 17 are swung toward each other to effect a gripping of the article, the clamping members 16 and 17 are locked in clamping position and will remain in locked clamping position until forcibly separated.

We claim:

1. A pliers comprising a pair of elongated handles, means pivotally securing the outer ends of said handles together, a pair of elongated clamping members having opposed clamping jaws on the outer ends thereof, means pivotally securing the inner ends of said members to said handles in offset relation with respect to said first named pivot means, and adjustable fulcrum means including a bolt of adjustable effective length extending through said members outwardly of the inner ends thereof and in the plane of swinging of said clamping members whereby rocking of said handles toward each other will move said clamping jaws toward each other, and whereby adjustment of the effective length of said bolt will vary the limits of movement of said

clamping jaws in both the opening and closing directions relative to each other.

2. A pliers comprising a pair of elongated handles, means pivotally securing the outer ends of said handles together, a pair of elongated clamping members having opposed clamping jaws on the outer ends thereof, means pivotally securing the inner ends of said clamping members to said handles in offset relation with respect to said first named pivot means, spring means interposed between said clamping members for constantly urging said members apart, and adjustable fulcrum means for said clamping members disposed outwardly of the inner ends thereof, said fulcrum means including a bolt of adjustable effective length extending through said clamping members at right angles to said second named pivot means whereby rocking of said handles toward each other will move said clamping jaws toward each other, and whereby adjustment of the effective length of said bolt will vary the limits of movement of said clamping jaws in both the opening and closing directions.
